The ornamental design for a pusher plow blade system, as shown and described.

DESCRIPTION

FIG. 1 is a perspective view of a pusher plow blade system showing our new design, the system composed of a side adapter blade and a modular array of skid shoes mounted thereto shown in assembled condition;

FIG. 2 is a side elevational view thereof;

FIG. 3 is a front elevational view of the side adapter blade shown unassembled for ease of illustration;

FIG. 4 is a rear elevational view thereof;

FIG. 5 is a cross-sectional view thereof taken along lines 5-5 in FIG. 3;

FIG. 6 is a partial cross-sectional side elevational view of the frame shoe shown unassembled for ease of illustration;

FIG. 7 is a partial cross-sectional front view thereof;

FIG. 8 is a bottom plan view thereof;

FIG. 9 is a partial cross-sectional side elevational view of a fore and aft skid shoe shown unassembled for ease of illustration;

FIG. 10 is a top plan view thereof; and,

FIG. 11 is a front elevational view thereof.

The broken line showing of a blade is included for the purpose of illustrating environmental structure only and forms no part of the claimed design.
